Primary Examiner — Barbara Fox*Assistant Examiner* — Dana K Weiland(74) Attorney, Agent, or Firm — Dergosits & Noah LLP; Todd A. Noah(57) CLAIM

The ornamental design for a display screen with graphical user interface, as shown and described.

DESCRIPTION

The FIGURE is a front view of a display screen with graphical user interface showing our new design. The broken-line showing of the outermost rectangle and the two concentric circles in the lower center represents environment. The remainder of the broken lines illustrate the display screen with graphical user interface. The broken lines form no part of the claimed design.
